Primary Examiner—Brian N Vinson(74) Attorney, Agent, or Firm—Ogilvy Renault, LLP(57) CLAIM

The ornamental design for a vomit bag holding device, as shown and described.

DESCRIPTION

FIG. 1 is a perspective view of a vomit bag holding device, showing my new design;

FIG. 2 is a left side view thereof, the right side being a mirror image thereof;

FIG. 3 is a front view thereof;

FIG. 4 is a rear view thereof;

FIG. 5 is a top view thereof;

FIG. 6 is a bottom view thereof; and,

FIG. 7 is a perspective view of the vomit bag holding device shown in FIG. 1 having a vomit bag mounted thereto.

The parts shown in broken lines are environmental only and form no part of the claimed design.
